(57) **CLAIM**

The ornamental design for a display screen with graphical user interface for displaying device information, as shown and described.

DESCRIPTION

FIG. 1 is a front view of a first embodiment of a display screen with graphical user interface for displaying device information, showing the new design;

FIG. 2 is a perspective view of a second embodiment thereof;

FIG. 3 is a front view of the embodiment shown in FIG. 2;

FIG. 4 is a right side view thereof;

FIG. 5 is a left side view thereof; and,

FIG. 6 is a bottom view thereof.

The broken line showing of a device illustrates environment and forms no part of the claimed design. The outermost solid lines shows the display screen and forms part of the claimed design.

1 Claim, 6 Drawing Sheets
